United States Patent Office.

SIDNEY VAN AUKEN AND JAMES H. GRAHAM, OF BINGHAMTON, NEW YORK.

Letters Patent No. 66,753, dated July 16, 1867.

IMPROVED MILK-STRAINER.

The Schedule referred to in these Letters Patent and making part of the same

TO ALL WHOM IT MAY CONCERN:

Be it known that we, SIDNEY VAN AUKEN and JAMES H. GRAHAM, of Binghamton, in the county of Broome, and State of New York, have invented a new and improved Apparatus for Straining Milk; and we do hereby declare that the following is a full and exact description thereof, reference being had to the accompanying drawings, making a part of this specification, in which—

Figure 1 is a perspective view of our improvement, representing it as ready to be attached to the pail.

Figure 2 is an inverted view, showing the manner of securing it to the pail.

Figure 3 represents the wire strainer, one of the cams and the spring that holds the strainer in its place detached from their positions.

Like letters of reference indicate like parts.

The nature of our invention consists in the employment of a detachable milk-strainer frame so constructed that it can be readily and securely attached to and detached from the pail, together with the arrangement for securing the strainer in the mouth of the cover by means of a detachable spring fitted to hold it in position, so that it may be removed and cleansed or replaced by another without soldering.

To enable others to make and use our invention, we will describe its construction and operation.

We make the frame A of malleable cast iron, or other suitable metallic substance, and of a semicircular form, near the edge of which we cut a groove, B, for the purpose of inserting a strip of India rubber, C, which we place in it for the purpose of preventing leakage at the connections around the rim of the pail. The frame A is secured to the rim of the pail by means of two grooved cams D D, with handles, which work on a pin projecting through from the outside of said rim, and placed low enough to receive the rim of the pail between the rubber C and the diminished part of the cams. In the mouth E of the cover F we place the strainer G, which is cut the proper form and size. We then place it in the lower part of said mouth, where it rests upon an inside flange, and is held in its position by the spring H, which is bent to the proper form, so that it may be sprung in and removed by pressing the two ends I I together.

When we use our invention we select the proper size for the pail, place it upon the rim, then turn down the cams D D, which secures it from leaking by the pressure of the rim of the pail against the rubber C. It is then ready for use. When necessary to cleanse the pail, the strainer-frame is removed by simply turning down the cams, and if the wire strainer G in the mouth of the cover should become foul it is conveniently cleansed by removing it, which is accomplished by pressing the two ends I I of the spring together and slipping it out with the fingers. The ordinary mode of securing the wire strainer G in its place is by soldering, making it more difficult to cleanse, and when necessary to replace it it can only be done at the shop, which, under some circumstances, would be quite inconvenient.

We are aware that there are in use strainers that are attached to the pail by other appliances than by soldering, but they are different in construction from our improvement, being more expensive and not as easily kept in the proper condition for use. We therefore disclaim any interference with such, and confine ourselves only to the novel features of our invention.

Having thus described our invention, what we claim, and desire to secure by Letters Patent, is—

The frame A and the mode of attaching it to the pail, in combination with the detachable strainer G and the spring H, all constructed substantially as herein described and represented for the purpose set forth

SIDNEY VAN AUKEN,
JAMES H. GRAHAM.
